Carpets

No. 5,639

Mar. 12 1872.

UNITED STATES PATENT OFFICE.

ALPHONSE J. BOUËT, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,639, dated March 12, 1872.

To all whom it may concern:

Be it known that I, ALPHONSE JOANNIN BOUËT, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new configuration of ornamental figures of carpets, there being two such main figures, A B, and one, C, of lesser importance and magnitude. The design of the figure A is particularly extensive and ornamental, so much so that a detailed description would be too lengthy, its representation by the photograph being therefore entirely referred to. The figure B is similar

in ornamental style to A, though smaller and somewhat simpler, as shown, while the figure C is of simple outline with narrow side strips *a a* and projecting tufts *b b*, as shown. My invention also consists in the new ornamental scroll-work D, which fills the space between the figures A, B, and C, as shown.

I claim as my invention—

1. The design of the figure A, as shown.
2. The design of the figure B, as shown.
3. The design of the figure C, as shown.
4. The design of the scroll-work D, as shown.
5. The design for the carpet, composed of the figures A B C and scroll-work D, as shown.

ALPHONSE JOANNIN BOUËT.

Witnesses:

JAMES MORTON,
Solicitor, Kidderminster, England.
CHARLES FROST, *his clerk.*
